MAGNETIC FIELD SENSING APPARATUS

Barry D. Van Koevering, Saline, Mich., assignor to
AZA Scientific, Inc., Saline, Mich., a corporation of
Michigan

Filed Dec. 11, 1967, Ser. No. 9,728

Term of patent 14 years

Int. Cl. D10—07

U.S. Cl. D52—6

FIG. 1 is a perspective view of the front and right side of a magnetic field sensing apparatus in accordance with my design,

FIG. 2 is a rear elevational view of the design with the cord omitted,

FIG. 3 is an end elevational view as taken from the right of FIG. 1 with the cord omitted,

FIG. 4 is an end elevational view as taken from the left of FIG. 1 with the cord omitted, and

FIG. 5 is a top plan view of the design of my invention.

The dominant features of my design reside in the full line portions.

I claim:

The ornamental design for a magnetic field sensing apparatus, substantially as shown and described.
